UNITED STATES PATENT OFFICE.

ALEXANDER G. ALEXANDER, OF DETROIT, MICHIGAN.

MECHANISM FOR OPERATING DISCHARGE-VALVES.

SPECIFICATION forming part of Letters Patent No. 275,344, dated April 10, 1883.

Application filed October 3, 1882. (No model.)

To all whom it may concern:

Be it known that I, ALEXANDER G. ALEXANDER, of Detroit, in the county of Wayne and State of Michigan, have invented a new and useful Improvement in Mechanism for Operating Discharge-Valves, of which the following is a specification.

My invention consists in so combining the outlet-valve of a water closet or tank with a bucket adapted to hold water that when the valve is opened the bucket will hold said valve open until the water in said bucket escapes through a small orifice therein, and will then automatically close said valve.

15 Figure 1 is a plan view. Fig. 2 is a side view, partly in section. Fig. 3 is a vertical section. Fig. 4 is a perspective of the tipping bucket, and Fig. 5 is a side view of the bucket with its side wall partly broken away.

20 A represents the bowl of a water-closet.

B represents a trunk or chamber connected with bowl A by a pipe, I, and adapted at its bottom to connect with an ordinary soil-pipe. B is divided into two chambers by a wall or partition, as shown in Fig. 1. In the smaller of these chambers (marked H) is a ball-valve, F G, which controls the admission of water to bowl A through pipe N, there being a free water communication between pipe I and chamber H through pipe S, Fig. 2. The pipe S should be of a diameter considerably larger than the pipe N, so that the water can readily flow from the bowl A to chamber H. As the water in the bowl and chamber will stand at the same

35 level, the chamber should be so arranged that the water-line at which the float or ball-valve FG will close will be the line at which it is desired to hold the water in bowl A. Water will enter the bowl A from service-pipe through pipe N, and from thence it will pass through pipe S into chamber H. When the water in the chamber H rises so as to reach the float G it

40 will raise the same, closing the valve F and shutting off the supply through pipe N. The end of pipe I which opens into chamber B is beveled to form a valve-seat on the inner wall of said chamber.

45 C represents a bucket of peculiar shape, as shown in Figs. 4 and 5, hung on a shaft, O, journalled in the walls of chamber B. The point of attachment of said bucket C to shaft O is well to one side of the center of gravity

of said bucket, arm R being secured to said bucket for that purpose. Bucket C is made in two parts, v and V, separated by a wall, e, 55 in which is a hole, t. Part V is covered at the top, and has in its rear edge a hole, T. To the bottom of part v is secured a valve, J, adapted to fit the valve-seat on the end of pipe I. Through valve J is cut a hole, j, so that the 60 water in bowl A and pipe I passes freely into bucket C, and stands at the same height in said bowl and bucket, and said bucket serves as an overflow in case valve F should fail to work.

65 K L represent inclined planes or wedges, secured respectively to the outer wall of bucket C and the inner wall of chamber B, and coact to force valve J against its seat D.

P represents a pull-rod attached to the end 70 of a crank-arm, p, fastened on the end of shaft O.

The operation of my invention is as follows: Bucket C being in the position shown in Figs. 1, 2, 3, water will pass into bowl A through pipe N, and will rise in said bowl and bucket 75 until shut off by valve F. On raising pull-

P shaft O will be rocked and bucket C will be tipped toward the left, Fig. 1, until it strikes the rear wall of chamber B, thus opening valve J and allowing the contents of 80 bowl A to discharge through pipe I and chamber B. The water in part v of bucket C escapes through holes j and t, and the weight of water in part V of said bucket holds said bucket tipped until the water therein has escaped 85 through hole T, thus holding valve J open. It is evident that the time during which said valve will be held open may be regulated by increasing or diminishing the size of hole T. As soon as the water has escaped from bucket 90 C the weight of said bucket causes it to fall back to its original position, wedge K strikes against wedge L, and valve J is forced to its seat.

95 It is obvious that the principle of my invention may be applied to valves differing in construction from the valve shown in the drawings, and I do not wish to limit myself to any particular form of valve.

What I claim as my invention, and desire to 100 secure by Letters Patent, is—

1. The combination, with the discharge-valve of a water closet or tank, of a tipping bucket arranged to be filled with water from the bowl

of the closet, and adapted, when tipped, to hold said discharge-valve open until the water contained in said tipping bucket escapes through a small orifice therein, and then automatically close said valve, substantially as set forth.

2. In combination with the discharge-valve of a water closet or tank, a tipping bucket arranged to be filled with water from the bowl of the water-closet, hung on a pivot at one side 10 of its center of gravity, and so proportioned that when partially filled with water and tipped the weight of the water therein contained will transfer the center of gravity to the other side of said pivot until said water 15 has escaped, substantially as set forth.

3. In combination with the discharge-valve of a water closet or tank, the bucket C, hav-

ing parts *v* V and hole T, hung on shaft O, connected with the discharge-valve, and provided with a suitable mechanism whereby the 20 same may be tipped, substantially as herein set forth.

4. The combination of the tank B, having the inclined plane or wedge L, and the bucket C, provided with the inclined plane or wedge 25 K, the faces of said inclined planes or wedges acting together to press the valve J, carried by the bucket C, to its seat, substantially as and for the purposes described.

A. G. ALEXANDER.
